UNITED STATES PATENT OFFICE.

ROBERT A. HORNE, OF BIRMINGHAM, ALABAMA.

POWER-PRESS.

1,266,684.

Specification of Letters Patent.

Patented May 21, 1918.

Application filed November 13, 1917. Serial No. 201,814.

To all whom it may concern:

Be it known that I, ROBERT A. HORNE, a citizen of the United States of America, residing at Birmingham, in the county of 5 Jefferson and State of Alabama, have invented certain new and useful Improvements in Power-Presses, of which the following is a specification.

My invention relates to a power press 10 adapted for pressing, shaping, forming and shearing metal sheets and bodies.

One object of my invention is to design a power press in which the power is applied in a novel and effective manner through a 15 multiplying train of levers and preferably from a single power cylinder to operate the movable element of the press with the power and length of stroke requisite for the work in hand.

20 A further object is to so design the press that it can be cheaply and quickly constructed of standard structural metal parts which can be readily assembled at the point where the press is to be built.

25 The objects and advantages of my invention as to its various novel details of construction will be better understood by reference to the accompanying drawings wherein I have sought to illustrate only the preferred embodiment of my invention.

According to the drawings:

Figure 1 illustrates my power press in side elevation with the movable member raised.

30 Fig. 2 is a vertical sectional view taken on the line 2—2 of Fig. 1.

Fig. 3 is an end elevation of Fig. 1.

Fig. 4 is a part plan and part sectional view taken on the line 4—4 of Fig. 1.

40 Fig. 5 is a detail sectional view of the motor and its valve control; and

Fig. 6 is a detail view of the cross head on the piston.

Similar reference numerals refer to similar parts throughout the drawings.

I have illustrated my invention as mounted on a concrete foundation 1 having an intermediate recess or seat 2 therein below the level of the floor 3. In this recess 45 I mount a vertical steam or compressed air cylinder 4, the base of which is suitably anchored to the foundation while its top head stands flush with the top of the foundation 1. On opposite sides of the cylinder head

are rigidly attached the base flanges 5 of two vertical guide plates 6 having oppositely disposed alining vertical slots 7 therein lying in a plane which bisects the axis of the cylinder. At its upper corner edges each of these plates 6 is rigidly bolted to the brace bars 8 preferably formed by an integral bent bar riveted at its center 9, which is twisted to lie horizontally to the stationary or bed member 10 of the press. The lower ends of these braces 8 are made fast on opposite sides to the lower ends of upright channel bars 11 which form the vertical elements of the frame work. A pair of these channels 11 are arranged at each end of the press with their flanges out-turned and their webs disposed in spaced parallelism and each channel has an angle bar 12 riveted to its lower end and connected by anchor bolts 13 to the foundation 1.

The stationary or bed member 10 of the 75 press is built up of structural parts, the preferred construction being illustrated in Fig. 2, where a center I-beam 14 is connected by rivets 15 to channels 16, one of which is placed on each side of the I-beam and spaced therefrom by a filler block 17 which fits between the opposing flanges of the channel and the I-beam. The bed member is designed to fit between and to be rigidly secured by rivets 18 to the pairs of upright channels 11 at each 80 end thereof, thus forming an intermediate spacer and transverse tie connection for the frame work.

The movable or presser member 19 of the power press is built up of structural members 14^a, 15^a, 16^a and 17^a, in the same manner as the bed is built of the corresponding parts 14, 15, 16 and 17 already described. The presser member is free to slide vertically between the pairs of upright channels 11 at its 90 ends, and to prevent endwise displacement I bolt vertical guide bars 20 on each side at its ends and dispose them to bear against the inner flanges of the frame channels 11.

The mechanism for operating the presser member 19 is connected thereto at each end and comprises two pairs of pivotally connected toggle links 21, 22, the lower link of each toggle being pivotally connected to a bracket 23 riveted to the top flange of the 100 adjacent channel 16^a and the upper link of each toggle being pivotally connected to a bracket 24 adjustably connected by bolts to

the inner flange of the adjacent channel 11 near its upper end. The links forming the pair of toggles at each end of the presser element 19 are connected together by a pair 5 of arms 26 to a bar 27, the arms being placed on each side of the bar and each provided with a series of holes 28 adapted to receive a cross pin 29, which at its center is passed through one of a series of holes 27^a in the 10 vertical bar 27 and at its ends is made fast to the free ends of a pair of rocker arms 30 pivotally connected to adjustable brackets 31 that are bolted to the outer flange of the adjacent channel 11. The lower end of each 15 bar 27 is pivotally connected to the outer end of a power lever arm 32 which, as shown, is pivotally mounted near its outer end on a fulcrum pin 33 which is mounted in a pair of bearing plates 34 riveted to and projecting inwardly from the webs of the adjacent 20 channels 11. An additional bearing hole 35 for each fulcrum pin 33 is provided nearer the outer end of each lever to increase the leverage and reduce the length of stroke, 25 this hole intersecting the bearing plate 34 and the webs of the channels 11 to which the plates are riveted. The levers 32 extend inwardly from opposite sides toward and beyond the center line of the press where 30 their ends are provided with elongated slots 36 that are received in a cross head or yoke 37 on the top of the piston rod 38 and are pivotally connected thereto by a pin 39 which extends through and beyond the yoke 35 arms. A pair of roller sleeves 40 and 41 are mounted on the pin 39 and each form a roller bearing working in the slot 36 of its respective lever. Cotter keys 42 hold the pin 39 in position in the yoke while the ends of 40 the pin project sufficiently on each side to enter and be guided by the slots 7 in the plates 6.

The piston rod 38 is connected to a piston 43 in the power cylinder 4 and steam or air 45 pressure is admitted to opposite ends of the cylinder through ports 44 and 45 as supplied by a pressure pipe 46 under control of a rotary valve 47 which also controls the exhaust from the cylinder. This valve has a 50 valve arm 48 connected to a foot pedal rod 49 which projects downwardly through the floor 3 and through a spring cage 50 in which is mounted a spring 51 that normally holds the pedal in raised position which 55 moves the valve to lower the plunger 43.

To operate the press, the treadle 52 is depressed, the power medium forces the piston 43 upwardly, and the yoke 37 rocks the power levers on their respective fulcrum pins 33 to move their outer ends downwardly with a greatly multiplied power. The motion of the outer ends of the levers is 60 transmitted by means of the bars 27, and pins 29 to rocker arms 30 and arms 26 to the hinge pins 25 for the several pairs of toggle 65

links 21, 22, and as these are drawn outwardly, the presser member 19 is forced downwardly with increasing power as the toggle links approach straight line position. This accomplishes the power stroke and 70 when completed, the foot pedal 52 is released, power is reversed in the cylinder and the train of connections described moves reversely to raise the presser member to its elevated position shown in Fig. 1. The 75 parts thus described are arranged for the maximum length of stroke for the presser member, but not for its maximum power. To obtain a shorter but more powerful stroke, the fulcrum pins 33 for the levers 32 80 are shifted to position in the holes 35, thus greatly augmenting the leverage power applied at the outer ends of the levers to the bars 27. In order to accommodate the position of the presser member to this variable 85 length of stroke for the bars 27, I make use of the series of holes 28 in the arms to change the pin 29 to the hole which will bring the toggle links to the desired position relative at the commencement of the stroke 90 so that they will, at the conclusion of the stroke, bring the presser member to the desired position.

In order to adapt the press for a wider range of usefulness the presser member 95 should be adjustable to work on thick or thin stock and to this end I provide the flanges of the channels 11 with a series of bolt holes 55 above the positions of each bearing bracket 31 and 24 so that the bolts 100 securing these brackets may be set to a greater height above the bed 10. As the bearing brackets 31 are raised the pins 29 are shifted to the proper holes 27^a in the bars 27 and the brackets 24 are similarly adjusted, 105 but it will be obvious that the bearing brackets 24 may be independently adjusted without changing the position of the brackets 31 and thus afford a further means of modifying the toggle motion. These adjustments 110 can be readily performed and make the press adaptable to a great variety of work.

My press is adapted for various uses such as forming, shearing, pressing or shaping metals, or for the operation of metal riveters 115 53 which are shown in Fig. 2 as having a supporting member 54 suitably secured to the bed 10 and adapted to hold the riveters projecting in proper operating position with the upper or movable riveter member disposed in the path of the presser head so that the lowering of the latter will operate the riveter. Shears may be similarly connected and operated. This arrangement is of special benefit where the apparatus is used for 120 the manufacture of elevator buckets and like members requiring shearing, shaping, bending and riveting operations.

It will be obvious that my press can be 125 readily assembled from standard structural 130

material and that it can be taken down and transported in collapsed form and at small expense. The leverage arrangements shown are capable of operating with high terminal pressures derived from a relatively small initial pressure, and the press as a whole will take the place of very heavy, cumbersome and expensive machinery which is all the market now affords for the class of work for which this apparatus is suitable.

This invention is not intended to be restricted in scope to the specific embodiment shown, but contemplates such modifications as come within the spirit and scope of the claims.

Having thus described my invention, what I claim as new and desire to secure by Letters Patent, is:—

1. A press comprising a frame, a bed member mounted in the frame, a movable presser member guided in the frame, toggles for imparting motion to the presser member, power multiplying levers adapted to operate the toggles to move the presser member, and a common power cylinder for operating said leverage mechanism.

2. A power press of the character described comprising a frame work of vertical structural members, a horizontal bed member cross connected to the upright members, a base to which the upright members are anchored, a presser member guided by said upright members, toggles connecting the presser member to the upright members, a power element, power multiplying transmission levers between said element and toggles to open and close the latter and operate the presser member, and supports for said connections.

3. A power press of the character described comprising a frame work of vertical structural members, a horizontal bed member cross connected to the upright members, a base to which the upright members are anchored, a presser member guided by said upright members, toggles connecting the presser member to the upright members, means to vary the point of connection of the toggles to said upright members, a power element, power multiplying lever forming transmission connections between said element and toggles to open and close the latter and operate the presser member, and supports for said connections.

4. A press comprising a frame, a bed member mounted in the frame, a movable presser member guided in the frame, toggles for imparting motion to the presser member, a power multiplying leverage mechanism adapted to operate the toggles to move the presser member, a common power cylinder for operating said leverage mechanism, and means to vary the length of stroke of the leverage mechanism to increase its power and modify the toggle movement.

5. A press comprising a frame, a bed member mounted in the frame, a movable presser member guided in the frame, toggles for imparting motion to the presser member, a power multiplying leverage mechanism adapted to operate the toggles to move the presser member, a common power cylinder for operating said leverage mechanism, means to vary the length of stroke of the leverage mechanism to increase its power, and means to shift the position of the toggles relatively to said bed member.

6. A press comprising a frame, a bed member mounted in the frame, a movable presser member guided in the frame, toggles for imparting motion to the presser member, a power multiplying leverage mechanism adapted to operate the toggles to move the presser member, a common power cylinder for operating said leverage mechanism, means to vary the length of stroke of the leverage mechanism to increase its power, means to shift the position of the toggles relatively to said bed member, and means to adjust the parts of said leverage mechanism to accommodate it to changes in stroke and in position of the toggles.

7. A power press of the character described comprising a frame work of vertical structural members, a horizontal bed member cross connected to the upright members, a base to which the upright members are anchored, a presser member guided by said upright members, toggles hung from the upright members and connected to the presser member, a power cylinder, a piston therefor, power multiplying leverage connections between said piston and toggles to open and close the latter, and fulcrums for the leverage connections adjustably mounted on said upright members to vary the power applied to the presser member.

8. A power press of the character described comprising a support, upright members mounted thereon, a bed member connecting the upright members, a power cylinder below the bed member, a vertically movable piston in said cylinder, oppositely disposed levers having a lost-motion connection at their adjacent ends to said piston, a presser member guided in said uprights, toggles connecting the presser member to the uprights, and operating connections between the outer ends of the levers and the toggles to open and close the latter and move the presser member, substantially as described.

9. A power press having a frame comprising uprights on each side, a bed rigidly connected to the uprights, a cylinder vertically disposed beneath the bed, means to brace the cylinder to the frame work, a plunger operated by the cylinder, a cross pin carried by the plunger, vertical guides for said pin, levers having lost-motion connections at their inner ends to said pin, fulcrums for

said levers on said frame work, a vertically movable presser member guided by said frame, and operating connections between said levers and presser member, substantially as described.

10. A power press having a frame comprising uprights on each side, a bed rigidly connected to the uprights, a cylinder vertically disposed beneath the bed, means to brace the cylinder to the frame work, a plunger operated by the cylinder, a cross pin carried by the plunger, vertical guides for said pin, levers having lost-motion connections at their inner ends to said pin, adjustable fulcrums for said levers on said frame work, a vertically movable presser member guided by said frame, and adjustable operating connections between said levers and presser member, substantially as described.
15. 11. In a power press, a frame, a bed, a movable presser member, toggles connecting said member to the frame, bars connected to the toggle joints, rocker arms hinged to the frame and adjustably connected to said bars, levers fulcrumed to the frame at each side, rods connecting the levers to said links and

bars, and a motor to move said levers and operate the presser member.

12. In a power press of the character described, a structural metal frame work comprising uprights formed of spaced pairs of channel bars, a bed inserted between the channels of each pair and made fast thereto, a presser member vertically movable between the channels toward and from the bed, a toggle connecting each channel bar to the presser member, a common pivot pin for connecting the links of each adjacent pair of toggles, a number of rocker arms connected to the outer edges of the channels, levers fulcrumed to the base of the uprights, power means to rock the levers vertically, links connected to the outer ends of the levers, and means connecting said links to said rocker arms and to the bars that are in turn connected to the toggle pivot pins, substantially as described.

In testimony whereof I affix my signature.

ROBERT A. HORNE.
